UNITED STATES PATENT OFFICE.

JOHN J. BRANAGAN, OF MCKEES ROCKS, PENNSYLVANIA

RAILROAD-TIE.

1,256,199.

Specification of Letters Patent. Patented Feb. 12, 1918.

Application filed December 7, 1917. Serial No. 205,927.

To all whom it may concern:

Be it known that I, JOHN J. BRANAGAN, a citizen of the United States, and a resident of McKees Rocks, in the county of Allegheny and State of Pennsylvania, have invented a new and useful Improvement in Railroad-Ties; and I do hereby declare the following to be a full, clear, and exact description thereof.

10 My invention relates to improvements in ties, and more particularly to metallic ties for railways, and has for its leading object the provision of an improved form of railroad tie having formed thereon an improved 15 chair portion which will be durable and strong, and which will eliminate the necessity of using spikes or bolts for joining and securing the rails to the ties.

Another object of this invention is to provide 20 a tie of this class which will positively prevent spreading of rails at any time, and one which may be readily disassembled to allow removal and replacement of worn rails.

25 Another object is to provide a tie of the above mentioned class which will allow for the longitudinal expansion and contraction of the rails due to change in temperature.

Other objects, such as trussing and general reinforcing of the tie base and its 30 associated parts in such manner as to facilitate rather than hinder the planting of the tie will be more fully brought out in the following specification and illustrated in the accompanying drawings.

It is well known that, in the use of the ordinary wooden tie to which bed plates, chairs and other such devices must be attached when laying a road, when the rails 40 themselves are applied on these attachments they must be spiked in position and the rail joints bolted.

Continual use of roads constructed with wooden ties will cause the spikes to become 45 loosened and the bolts to become worn in the joints, even before the rails themselves have become sufficiently worn to necessitate replacing them, thus requiring the spikes to be re-set and new bolts applied to the joints.

50 With the use of my improved tie absolutely no bolts or spikes are used, and therefore the re-setting of the ties and the application of new bolts and spikes are eliminated, as are also the bed plates, chairs and 55 such other contrivances as may be used.

In carrying out my invention I provide a

channeled or hollowed base having an improved chair portion at each end adapted to receive a rail and having movable parts in the form of wedges and clamping members 60 adapted to hold the rails securely in position.

While I have shown and described one particular form of my invention, it will be readily understood that I do not wish to be limited to the exact form shown, since various changes in design and details of structure may be made without departing from the spirit of my invention as defined in the appended claims.

In the drawings:

Figure 1 is a plan view of a section of railroad constructed with my improved tie;

Fig. 2 is a sectional view on the line 2—2 of Fig. 1;

Fig. 3 is an end view of one of the ties having a rail therein;

Fig. 4 is a longitudinal sectional view of one of the ties partly broken away;

Fig. 5 is a perspective view of the wedge member of my device;

Fig. 6 is a similar view of the clamping member; and

Fig. 7 is a view on the line 7—7 of Fig. 6.

Referring more particularly to the drawings, the letter A designates the base of my tie as a whole, which consists of a top 2 and sides 3, forming a channeled portion. The base A is suitably braced within the channel by web tie members 4, cross tie members 5, and the side portions have reinforcing flanges 6 on their outer face spaced at intervals, which also serve to prevent lateral movement of the tie. The bottom surfaces of the base are slightly rounded, as at 7, so as to present a deflecting face to any objects they may strike when the tie has been set or planted.

The chair members formed at each end of the base A are identical in construction, and therefore a detailed description of one of the chairs is deemed sufficient, it being understood however that the same reference numerals apply to the same parts of both chairs.

The chair is formed adjacent the end of the tie and comprises a locking flange 8 formed integral with the top portion of the base, having a suitably beveled groove 9 in its inner face adapted to receive the base flange 10 of an ordinary rail 11. The top face 2 of the base has a suitable channel 12

formed therein and a clamping member 13 is adapted to be slidably mounted in said channel portion and comprises a rectangular base portion 14 having a locking tongue 14^a adapted to engage in the base portion of the locking flange 8, an upwardly extending connecting rib 15, and a top portion which extends outwardly from the connecting rib 15 forming an extension or locking flange 16 adapted to overlie and firmly engage the base flange 10 of the rail, and a second extension or flange 18 extending at right angles to said connecting rib for the purpose to be described. At the inside transverse edge of the channel 12 is formed an upwardly extending transverse rib or abutment 19 having a rectangular groove 20 in its inner face, and having its inside face, below the slot 20, beveled rearwardly for the purpose to be described. A compound wedge member is adapted to be inserted within the channel 12 and comprises a lower wedge portion 21 and an upper wedge portion 22, the lower wedge portion 21 being adapted to have its side faces engage the side face of the clamping member 13 and the beveled portion of the transverse rib or abutment 19, while the upper wedge portion 22 is adapted to engage the inside face of the connecting rib 15 of the member 13, and to be held in such position by the overlying extension or flange 18, and to also be engaged within the groove 20 in the abutment or rib 19, and is thereby firmly locked in position.

It will be readily seen that when a rail is placed in position and the clamping member 13 is forced against the inside edge of the rail base 10, and the wedge 21-22 is driven into position, that the several parts will be bound firmly against movement.

After the wedge 21-22 has been driven into position, a cover plate 23 having end flanges 24 extending downwardly therefrom is adapted to cover the wedge members to prevent them from becoming clogged by dust, dirt, etc., and to prevent their working loose.

To further strengthen the tie base, a longitudinal bracing member or flange 25 is formed on the top face 2 of the base A and extends longitudinally between the chair portions. The bracing member 25 therefore strengthens the base to eliminate any danger of central cracking due to the shocks and weight on the outer end of such base.

The operation of my device is as follows:

The wedge 21-22 and the locking member 13 being removed from the channel 12, a rail is placed in position so that its bottom flange is engaged in the beveled groove 9 in the locking flange 8. The clamping member 13 is then inserted within the channel 12 and forced against the rail so that its flange 16 extends over and engages the other side 55 of the base flange 10 of the rail 11. The

wedge 21-22 is then inserted within the channel 12 and driven home, so that all parts are forced tightly together. The cover plate 23 is then placed in position so that the end flanges 24 abut the ends of the wedge 21-22, thereby locking the several parts together.

Having thus described my invention, what I claim as new and desire to secure by Letters Patent is:

1. A metallic tie of the class described comprising a base portion, a chair portion formed on each end of said base, each of said chair portions comprising a locking flange adapted to engage the base flange of a rail, an upwardly extending abutment formed integral with said base and spaced from said locking flange, a clamping member mounted between said locking flange and said abutment, said clamping member comprising a base portion, an upwardly extending connecting rib, and a top member extending transversely of said connecting rib, and a wedge member adapted to coöperate with said clamping member and abutment to securely bind said parts together. 90

2. A metallic tie of the class described comprising a channel shaped base portion having means formed thereon to prevent endwise movement thereof, a chair portion formed on each end of said base, each chair portion comprising a locking flange adapted to receive one side of the base flange of a rail, an upwardly extending abutment spaced from said flange and formed integral with said base portion, a clamping member slidably mounted between said locking flange and said abutment, and adapted to engage the one side of the base flange of a rail, and a wedge member adapted to coöperate with said abutment and said clamping member to securely bind said parts in position. 100

3. A metallic tie of the class described comprising a channel shaped base portion and means formed thereon to prevent endwise movement thereof, a chair portion formed on each end of said base, each of said chair portions comprising a locking flange adapted to engage the base flange of a rail, an upwardly extending abutment formed integral with said base and spaced from said locking flange, a clamping member slidably mounted between said locking flange and said abutment, said clamping member comprising a base portion, an upwardly extending connecting rib, and a top member extending transversely of said connecting rib, and a compound wedge member adapted to coöperate with said clamping member and abutment to securely bind said parts together. 110

4. A metallic tie of the class described comprising a channel-shaped base portion having means formed thereon to prevent endwise movement thereof, a chair portion 130

formed on each end of said base, each of said chair portions comprising a locking flange having a beveled groove therein at its base adapted to receive the base flange 5 of a rail, an upwardly extending abutment formed integral with said base and spaced from said locking flange and having a rectangular groove therein, a clamping member slidably mounted between said locking flange and said abutment, said clamping member comprising a base portion, an upwardly extending connecting rib, and a top portion extending transversely of said connecting rib and forming flange portions on

each side of said connecting rib, and a compound wedge member adapted to be engaged 15 between said clamping member and said abutment, and to have a portion thereof engaged within said rectangular groove of said abutment and under one of the flanges 20 formed by the top portion of said clamping member.

In testimony whereof, I, the said JOHN J. BRANAGAN, have hereunto set my hand.

JOHN J. BRANAGAN.
